(74) Attorney, Agent, or Firm — Novick, Kim & Lee,
PLLC; Jae Youn Kim(57) **CLAIM**

We claim the ornamental design for a lid for sample storage container, as shown and described.

DESCRIPTION

FIG. 1 is a perspective view of a lid for sample storage container, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dash-dash broken lines in the drawings show portions of the lid for sample storage container that form no part of the claimed design. The dot-dash broken lines in the drawings depict the boundaries of the claim and form no part thereof.
